UNITED STATES PATENT OFFICE.

HERMAN KIMBALL ANSINGH, OF MURRAYSVILLE, PENNSYLVANIA, ASSIGNOR TO
WESTINGHOUSE ELECTRIC & MANUFACTURING COMPANY, A CORPORATION OF
PENNSYLVANIA.

SWITCH LATCH.

Application filed March 28, 1920. Serial No. 367,994.

To all whom it may concern:

Be it known that I, HERMAN KIMBALL ANSINGH, a citizen of the United States, and a resident of Murrysville, in the county of 5 Westmoreland and State of Pennsylvania, have invented a new and useful Improvement in Switch Latches, of which the following is a specification.

My invention relates to electric switches 10 and particularly to latching means for switches of the kind ordinarily known as disconnecting switches.

One object of my invention is to provide a device of the above indicated character 15 that may be readily applied to a switch and that shall be capable of a certain rocking movement thereon to ensure effective co-operation with the movable member of the switch.

Another object of my invention is to provide a latching device for a disconnecting switch that shall be simple and durable in construction and economical to manufacture.

In practicing my invention, I provide a latching device comprising rearwardly-extending jaws forming an opening through which a terminal member, mounted on the jaw member of the switch, loosely extends 25 to form a pivot. The front part of the latch member is adapted to embrace the upper part of the switch blade member which is provided with an opening for the reception of an operating rod or hook. The projecting front portion of the latch member 30 is bevelled so that, when the blade member is moved from its open to its closed position, it will lift the latch member, thus, rocking the latter on the rear terminal member and 35 permitting the blade member to be moved to its closed position. After the operating hook is withdrawn from the opening in the blade member, the latch member will fall over and lock the blade member in position.

In order that the latch member may be 40 lifted for the purpose of releasing the blade member, when it is desired to open the switch, the sides of the latch member are arranged to only partially cover the opening 45 in the blade member so that the operating hook, when pushed into the opening in the blade member, will raise the latch member sufficiently to release the blade member.

In the accompanying drawings, Fig. 1 is 50 a side elevational view, showing the break-

jaw members and the upper part of the blade member of a disconnecting switch provided with an automatic latch device constructed in accordance with my invention; Fig. 2 is a plan view of the same; Fig. 3 60 is a side view, partially in elevation and partially in section, of a modified form of my improved latch device for use in connection with a horizontally disposed switch, and Fig. 4 is an end view of the device 65 shown in Fig. 3.

As shown in Figs. 1 and 2, terminal jaw members 1, of a disconnecting switch, are adapted to receive the free end of a blade member 2 of the switch. The jaw members 70 1 are provided with an upwardly projecting terminal member 3 to which a conducting lead (not shown) may be connected. A portion 4 of the blade member, which projects above the jaw members when the 75 switch is closed, is provided with an opening 5 through which a hook at the end of a rod or pole (not shown) is passed when it is desired to open or close the switch.

A latch member 6, preferably constructed 80 of metal, is provided with rearwardly and inwardly-extending jaw portions 7 to form an opening 8 in which the terminal member 3 is loosely disposed. The upper edge of a transverse partition 9 of the member 6, adjacent the opening 8, is chamfered to permit the member 6 to tilt up and down on the terminal member 3. The front part of the latch member 6 has an opening 10 that receives the upper part 4 of the blade member, when the latter is in its closed position, and is provided with a bevelled portion 11 that, as the blade member is moved to position between the jaw members 1, the edge thereof will engage the bevelled portion and 90 lift the latch member sufficiently to enable the blade member to pass between the jaws, whereupon, the latch member falls back into the position shown and locks the blade in place.

The latch member is provided with a notch 12, in each side, which is opposite, and partly covers, the opening 5 in the blade member when the latter is locked in position. After the latch member 6 has been slightly 105 lifted, by forcing the operating hook into the opening 5, a further slight movement of the blade member towards its opening position will cause the latch member to be further lifted by engagement of the hook with 110

an inclined part 13 of the notch 12, so that it assumes the position, as shown in dotted lines in Fig. 1, in which the blade member may be pulled away from the jaw members to break the circuit.

5 An application of my improved form of latch device to a horizontally-disposed switch is shown in Figs. 3 and 4 in which a spring 14 is connected, at one end, to a 10 screw 15 on the jaw members 1, and, at the other end, to a bar or bridge member 16 secured to, or formed integrally with, the latch member 6. The spring 14 tends to retain the latch member 6 in its latching position.

15 While I have shown and described particular forms of my invention, changes may be effected therein without departing from the spirit and scope thereof, as set forth in the appended claims.

20 I claim as my invention:

1. The combination with a knife-blade switch, of a latch device therefor comprising a latch member having a recess by which it entirely surrounds the blade member, the 25 said device loosely engaging a fixed portion of the switch.

2. The combination with a knife-blade switch, of a latch device therefor comprising a latch member formed and positioned to 30 entirely surround the free end of the blade member and means for loosely supporting the latch device from a fixed portion of the switch.

3. The combination with a knife-blade switch, of a latch device therefor comprising a stationary holding member extending substantially in the direction of the blade member in the closed position of the switch, and a latch device loosely mounted on said 35 holding member.

40 4. The combination, in a knife-blade switch, of a pivoted arm, a stationary member which the free end of the arm is adapted

to engage, a projection adjacent to the stationary member, and a latch device comprising 45 a member loosely mounted for free rocking movement and adapted to engage the said projection and the end of the arm to releasably maintain them in engagement.

5. In an electric switch, the combination 50 with a pivoted switch arm and a co-operating contact member for the free end of said arm, of a latching device comprising a member projecting from said contact member and a latch member loosely mounted on 55 said projecting member for rocking relation thereto and holding co-operation with the switch arm.

6. The combination with a knife-blade switch, of a latch device therefor comprising 60 a latch member having an opening at its forward end and an opening formed by rearwardly-extending jaws, and a member projecting loosely through said rear opening and constituting a pivot for the latch member, said forward opening automatically receiving the end of the blade member during the closing of the switch.

7. In a switch, the combination with a 70 stationary contact member and a knife-blade member having an opening adjacent to its free end, of a latch device therefor comprising a stationary holding member and a latch member having an opening at its forward end to receive the free end of the 75 blade member and an opening formed by rearwardly-extending jaws by which the latch loosely embraces said holding member, said latch member also having means by which the blade member is released when an 80 operating hook is placed in the opening in the blade member.

In testimony whereof, I have hereunto subscribed my name this 5th day of March 1920.

HERMAN KIMBALL ANSINGH.
